US0D1012121S

(12) **United States Design Patent** (10) **Patent No.:** **US D1,012,121 S**
(45) **Date of Patent:** **** Jan. 23, 2024**

(54) **DISPLAY SCREEN OR PORTION THEREOF WITH GRAPHICAL USER INTERFACE**

(71) Applicant: **Apple Inc.**, Cupertino, CA (US)

(72) Inventors: **Kevin Will Chen**, Cupertino, CA (US);
Christopher I. Wilson, San Francisco, CA (US)

(73) Assignee: **Apple Inc.**, Cupertino, CA (US)

(**) Term: **15 Years**

(21) Appl. No.: **29/895,279**

(22) Filed: **Jun. 20, 2023**

Related U.S. Application Data

(63) Continuation of application No. 29/859,839, filed on Nov. 14, 2022, now Pat. No. Des. 994,701, which is a continuation of application No. 29/834,281, filed on Apr. 11, 2022, now Pat. No. Des. 969,855, which is a continuation of application No. 29/704,811, filed on Sep. 6, 2019, now Pat. No. Des. 949,179.

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
